CLAIM

The ornamental design for a cable support, as shown and described.

DESCRIPTION

FIG. 1 is a perspective view of a cable support showing one embodiment of my new design;

FIG. 2 is a top view of the cable support shown in FIG. 1; FIG. 3 is a front view of the cable support shown in FIG. 1, a back view of the cable support being identical to the front view;

FIG. 4 is a bottom view of the cable support shown in FIG. 1;

FIG. 5 is a side view taken from the right in FIG. 3, a side view taken from the left in FIG. 3 being identical thereto;

FIG. 6 is a perspective view of a cable support showing another embodiment of my new design;

FIG. 7 is a top view of the cable support shown in FIG. 6; FIG. 8 is a front view of the cable support shown in FIG. 6, a back view of the cable support being identical to the front view;

FIG. 9 is a bottom view of the cable support shown in FIG. 6; and,

FIG. 10 is a side view taken from the right in FIG. 8, a side view taken from the left in FIG. 8 being identical thereto.

The broken line showing of cables in FIGS. 1 and 6 is for illustrative purposes only and forms no part of the claimed design.
